INTERNAL COMBUSTION LOCOMOTIVE

Filed Jan. 16, 1922

UNITED STATES PATENT OFFICE.

SIGNED MATTIAS BÄCKSTRÖM, OF STOCKHOLM, SWEDEN, ASSIGNOR TO AKTIEBOLAGET VAPORACKUMULATOR, OF STOCKHOLM, SWEDEN, A CORPORATION.

INTERNAL-COMBUSTION LOCOMOTIVE.

Application filed January 16, 1922, Serial No. 529,788, and in Sweden January 22, 1921.

Internal combustion engines and especially Diesel-engines which are used with great advantage in stationary plants and vessels have not hitherto been used to any greater extent in railway service depending partly on the fact that the internal combustion engines cannot develop any notable starting torque and partly on the fact that they do not answer the requirements for 10 overload capacity, which is necessary in railway service in up-grades and curves.

This invention has for one purpose to provide improved means for propelling locomotives and consists, in the preferred form, in 16 a combination of a Diesel or other internal combustion engine and a steam storer wherein the normal operations are effected by means of said combustion engine while the starting and certain overload operations are 20 effected by means of steam supplied by the storer.

Another purpose is to provide a novel and efficient arrangement of parts with respect to movable carriages as will more fully appear hereinafter. Other objects and advantages of the invention will be apparent as the description proceeds.

The invention will be fully described in connection with Figs. 1 and 2.

Fig. 1 shows a locomotive provided with an internal combustion engine and a steam motor and a tender on which a steam generator or boiler and a steam storer are arranged according to the present invention. 35 Fig. 2 is a modification of the tender mentioned above.

In Fig. 1, 1 indicates the internal combustion engine, and 2 the compressor belonging to the same. 3 is the steam motor, which is 40 connected with the steam storer 5 on the tender. 6 is a steam boiler, provided with a set of tubes 7. A conduit 8 connects exhaust gases from the internal combustion engine 1 to the steam boiler. 9 is the outlet for the 45 gases from the boiler. 10 indicates an oil burner, which is not always necessary. 11 indicates an arrangement, through which the steam is supplied to the storer. Storer 5 may also be supplied with steam from an 50 outside source through a conduit 12. Steam may be withdrawn from the storer through a conduit 13, for example, for heating the train. The storer is furthermore provided with a safety-valve 14.

The steam storer is a well insulated receptacle, filled to the greatest part with water or other substance adapted to store steam and heat. In this accumulator the heat of the exhaust gases of the internal combustion engine is stored in the form of heat of 55 fluid. These gases generally have a temperature of 500° Centigrade and therefore, rather a considerable quantity of heat may be recuperated from said waste gases. The operation of a locomotive according to the 60 present invention is as follows:

The starting operation is effected by steam produced from the water in the storer by drop of pressure occasioned by opening of the engine supply valve mechanism. The 70 steam thus produced passes to the steam engine 3, by means of which the train is brought in motion. The pressure will then gradually sink in the storer so long as steam is withdrawn. As is well known, the greatest 75 amount of power is required at the moment of starting when the pressure in the storer is the highest, which obviously facilitates an effective starting. After the train has been brought up to a fair speed in this 80 way, the steam is cut off and the Diesel-engine 1 switched in to take over the work from the steam motor 3.

The heat of the exhaust gases from the Diesel-engine is supplied, in the manner above described, to the steam boiler 6, from which boiler the steam generated by this heat is supplied to the storer through the charging apparatus 11. The storer will thus be charged by degrees during operation. 85 Just as in the case of starting, steam may be taken from the storer 5 to the steam engine 3 in order to obtain increased tractive effort in gradients, and the like. Obviously, steam may also be drawn from the storer for the 90 maneuvering of the Diesel-engine 1, for instance, for the starting and reversing thereof.

From the description above, it is evident that the storer is charged during operation 100 of the internal combustion engines and that starting and over-loads may be taken care of by means of steam from the storer.

Now, it is possible that when the Diesel-engine 1 is in operation the safety valve of 105 the steam storer will begin to blow off steam, by reason of too high a charge. In such case the load on the Diesel-engine 1 may be re-

duced, and the steam motor 3 caused to operate instead, so that the pressure of the steam storor is again reduced.

On account of the good insulation of the storor, the loss of heat of the same is so small that the charge of the storor may be maintained for several days when it is put out of operation and consequently a locomotive according to the invention is ready 10 for starting at any instant during the said period.

When required, however, the storor may be charged by supplying heat thereto in some other way, as above mentioned, for 15 instance, by firing with oil, that is to say, in cases where the storor happens to be discharged when the locomotive is to be put into operation, as well as on overloads of longer duration, in long gradients, when the 20 steam motor may be resorted to for assistance, as above mentioned.

In certain cases it may also be suitable to charge the storor in some way during the stops at the stations and this may take place 25 through the conduit 12, connected with the pipe between the storor and the boiler.

Fig. 2 is a modification of the tender above described which shows a combination unit 30 of steam boiler and storor. As before 5 is the steam storor. The exhaust gases from the internal combustion engine on the locomotive are supplied and they have to pass through conduit 8 and a set of tubes 7, arranged in the storor, whereby the water in 35 the same is heated. The gases leave the apparatus through the opening 9. Even here an oil burner 10 may be arranged to be used in case the storor should happen to be discharged when a start is to take place or 40 when it is necessary to handle overloads of a long duration. Withdrawal of steam for use in the steam engine on the locomotive can, as before, be effected through a conduit 4 or through a conduit 13 for other purposes, 45 for instance, for heating the train. Steam may also be supplied to the storor from any steam source through pipe 12. An even distribution of the supplied steam is obtained by a "steam distributor" 11, arranged in the 50 same way as described in connection with Fig. 1.

The present invention offers the following great advantages over previously known locomotives:

55 (1) On account of the employment of a steam motor, very great starting and overload torques may be obtained in the same manner as in a common steam locomotive, and such torques may be even greater by reason of the very great quantity of steam which is momentarily available.

(2) In comparison with the common steam locomotives, this locomotive shows an enormous saving of fuel consumption, in 60 that the thermal efficiency probably rises

from 3-7 per cent up to about that of the Diesel-engine. The new method also shows a considerable saving of fuel, as compared with the solutions previously suggested for this problem. This fuel economy is attained 70 partly because the losses connected with an electrical transmission may be avoided, and partly because the heat of the exhaust gases is utilized according to the present invention. 75

(3) As compared with electric transmission, the costs of construction will be much lower in the system according to the invention.

(4) Steam for heating the train may be and preferably is taken from the storor. 80

(5) Above all, the combination with a steam storor is advantageous in case it is suddenly necessary to apply brakes, such braking, as is well-known, being effectively 85 done with the aid of steam.

(6) The receptacle or the storor very effectively serves as a silencer.

(7) Moreover, this arrangement in particular shows that the locomotives now in use may easily be altered according to the 90 system forming the object of the present invention, whereby the capital cost thereof will be comparatively low.

While I have described a few preferred embodiments of my invention, it will be obvious that many variations are possible which fall within the scope of the invention and it is to be understood that I am not limited to the modifications shown and described. 95

• What I claim is:

1. The method of propelling a locomotive which comprises burning oil in an explosion engine and applying the force produced to drive the locomotive under normal running conditions, conducting exhaust gases from the explosion engine to a surface heater and transferring the heat therein to water and thereby producing steam, storing the steam thus produced in water, producing steam from the last mentioned water by drop of pressure at times when sufficient power cannot be obtained from the explosion engine, and utilizing the steam to produce power for driving the locomotive. 100 110 115

2. A locomotive comprising a steam motor, a Diesel engine, a steam storor, a steam boiler, means to conduct exhaust gases from said engine to said boiler, means to conduct steam from said boiler to said storor and means to release steam from the water in said storor by drop of pressure and to conduct steam from said storor to said steam motor. 120

3. A locomotive comprising a first movable carriage, a steam motor and a Diesel engine on said first carriage, a second movable carriage, a steam storor on said second carriage, means to transfer the heat of exhaust gases of said engine to water in said storor 125 130

and means to release steam from the water in said storor by drop of pressure and to conduct steam from said storor to said steam motor.

5 4. A locomotive comprising a steam motor, a Diesel engine, a steam storor, means to transfer the heat of exhaust gases of said engine to water in said storor and means to release steam from the water in said 10 storor by drop of pressure and to conduct steam from said storor to said motor.

15 5. A locomotive comprising a first movable carriage, a steam motor and a Diesel engine on said first carriage, a second movable carriage, a steam boiler and a steam storor on said second movable carriage, means to conduct exhaust gases from said engine to said boiler, means to conduct steam from said boiler to said storor, and means to release 20 steam from the water in said storor by drop of pressure and to conduct steam from said storor to said motor.

25 6. A locomotive comprising a Diesel engine, propelling means, a steam storor, means to transfer the heat of exhaust gases of said Diesel engine to said storor and means to release steam from the water in said storor by drop of pressure and to conduct steam from said storor to said propelling means.

7. The method of propelling a locomotive which comprises burning oil in an explosion engine and applying the force produced to drive the locomotive under normal running conditions, utilizing the exhaust 35 gases of the explosion engine to heat water, storing the water thus heated, producing steam from the water by drop of pressure at times when sufficient power cannot be obtained from the explosion engine, and 40 utilizing the steam to produce power for driving the locomotive.

8. A combined steam and internal combustion engine locomotive in which the steam generator is supported upon one 45 vehicle unit or truck and the steam and internal combustion engine cylinders together with their joint power transmission mechanism are carried by a separate truck or vehicle.

50 9. A combined steam and internal combustion engine locomotive in which the steam generator is supported upon one vehicle unit or truck and the steam and internal combustion engine cylinders together 55 with their driving gear are carried by a separate truck or vehicle.

In testimony whereof I affix my signature.

SIGURD MATTIAS BÄCKSTRÖM,
